UNITED STATES PATENT OFFICE

SIGMUND G. WEILER, OF MILWAUKEE, WISCONSIN

STOVE

Application filed October 30, 1932. Serial No. 403,585.

This invention relates to new and useful improvements in stoves and more particularly to a cooking stove.

One of the objects of my invention is the provision of a cooking stove wherein the articles being cooked are all enclosed, so that the odors therefrom will pass outwardly through a suitable conduit, thus providing an odorless, fire-proof and sanitary stove which will also eliminate the danger of gas explosion and incidental dangers from escaping gas due to the fact that any escaping gas will readily pass out through the conduit and not into the room in which the stove is located.

Another object of my invention is the provision of a cooking stove of the above character wherein the various burners on which articles are cooked are enclosed within suitable chambers which have outlets for conveying any odors, steam or the like, and prevents them from escaping into the room in which the stove is located, and at the same time is provided with movable shelves for supporting vessels above the burners whereby the vessels may be readily placed in position over the burners or removed therefrom.

A further object of the invention is the provision of a stove of the above character wherein the burners in certain of the compartments are arranged one above the other and the conduits leading to the burners are controlled by a novel valve construction whereby one or more of the burners may be readily connected to the fuel supply and the fuel easily regulated so that should it be desired to use only one of the burners, this can be done without the necessity of using any of the other burners, or all of the burners may be used simultaneously.

A still further object of the invention is the provision of a stove of the above character which has incorporated in its construction, suitable cabinets for the storage of cooking utensils and also for the purpose of retaining cooked foods in a heated condition until served.

With the above and other objects in view, the invention consists in the novel features of construction, the combination and arrangement of parts hereinafter more fully set forth, pointed out in the claim and shown in the accompanying drawings wherein:

Figure 1 is a front elevation of a cook stove constructed in accordance with my invention;

Figure 2 is a vertical sectional view;

Figure 3 is a detail section illustrating the arrangement of the valves which control the leads to the burners;

Figure 4 is a detail sectional view through one of the valves, illustrating its connection with three separate burners and the supply conduit;

Figure 5 is a perspective view of a hook member to be used in connection with the movable supporting grates; and

Figure 6 is a detail section illustrating a slightly modified form of the invention.

Referring more particularly to the drawings 1 in general indicates the body of my improved stove having suitable supporting legs 2, and it will be noted that the base portion of the stove forms the main body and comprises a chamber 3 in which are arranged a number of burners 4, and supported above these burners in suitable guide ways 5 are the grate members 6 which have at their forward edges suitable eyelets 7 which can be engaged by the hook portion 8 of the rod 9, the rod having a suitable handle 10 for manipulating the same when removing the grate 6.

The burners 4 have leading thereto suitable conduits 11 which are connected to the supply pipe 12 through the medium of the valve 13. The particular construction of this valve 13 is illustrated in Figure 4, and includes a rotor 14 formed with a plurality of conduits 11 whereby connection between the supply pipe 12 and any one of the burners can be readily established.

The chamber 3 is closed at its front side

by means of a movable door 16 having a suitable handle 17, and mounted upon the hinges 18 whereby this door may be readily lowered for gaining access to the chamber 3 and the door is provided with a transparent panel 19 so that the entire interior of the chamber 3 may be viewed from the front of the stove.

The top portion of the stove is generally indicated at 20 and this top portion is divided into separate chambers by means of a partition 21 forming the two side chambers 22 and 22', said chambers having communication with the outlet pipe or conduit 23.

The partition 21 is provided with an opening 24 whereby any odors from either chamber may pass to the other chamber and then out through the pipe 23. This opening 24 allows for a thorough circulation of air around the articles being cooked in the upper chambers, so that the odors therefrom will be readily carried out through the conduit.

Within each of the chambers 22 and 22', I provide three separate burners and in chamber 22, it will be noted that two of the burners are arranged in a lowermost position and indicated at 25, while the upper burner 26 is arranged centrally and above the burners 25, suitable conduits 27 connecting the supply pipe 12 with the burners 25 and 26 and the fuel supply of said conduits being controlled by one of the valve members 13.

Arranged above the two sets of burners 25 and 26 are the grate members 6' which are mounted in the same manner as the main grate 6 in the chamber 3, and are provided with eyelets 7' to be engaged by the hook member 8.

The chamber 22' has the same number of burners as the chamber 22, but in this chamber the single burner 26' is arranged below the burners 25', the burners 25' being the uppermost burners in this chamber, and these burners 25' and 26' are connected by means of conduits 27' to the supply pipe 12 with one of the valve members 13. In chamber 22 suitable grates 6' are also provided which are slidably mounted within the guides in the same manner as the grate 6.

Both chambers 22 and 22' are provided with openings normally closed by means of the doors 28 having transparent panels 29 whereby the interior of these chambers may be readily viewed from the exterior of the stove.

Mounted between the front supporting legs and beneath the main body portion of the stove is a chamber 30 having suitable drawers 31 slidably mounted therein, in which various types of cooking utensils may be retained. Each of the drawers 31 has a handle 32 whereby the drawers may be readily slid outwardly to gain access thereto.

At each side of the upper chambers 22 and

22' of the stove, I provide suitable cabinets with access gained therethrough, through the doors 33 and these cabinets may be utilized for containing cooking utensils or for containing cooked foods where it is desired to maintain them in a heated condition until served.

In Figure 6, I have illustrated a slightly modified form of the invention wherein the opening 24 and a similar opening 24' are normally closed by means of valve members. The opening 24' is formed in a horizontal wall 34 which is disposed between the chamber 3, and the upper portion of the stove, and permits the odors, steam and the circulation of air to pass upwardly through the chambers 22 and 22' and out through the conduit 23.

In Figure 6, it will be noted that the openings 24 and 24' are provided with slidable valve plates 35 and 35', whereby these openings may be maintained in an open or closed position as required, said valve plates having stems 36 which lead to the front part of the stove so that they can be readily actuated when desired.

It will be apparent from the foregoing description taken in connection with the accompanying drawings, that I have provided a novel type of cooking stove which will practically eliminate any odors from the cooking and will prevent the odors from escaping into the room in which the stove is located, but will carry them out through the conduit 23.

It will be also noted that by the particular arrangement of burners in my improved stove, several cooking utensils of different sizes can be used in the different compartments at one time, and one or more of the burners in each compartment can be used as desired.

The arrangement of burners is extremely useful and the use of the grates 6 and 6' is advantageous to a stove of this character as the different cooking utensils can be quickly and readily placed in position within the stove or removed therefrom.

While I have shown and described the preferred embodiment of my invention, it will be apparent that slight changes may be made in the construction when putting the invention into practice without departing from the spirit of the same or the scope of the appended claim.

I claim:

A stove of the class described including a body having supporting legs, said body being provided with superposed chambers, removable drawers arranged in the lowermost chambers, spaced burners arranged in the same general plane in the intermediate chamber, superposed burners arranged in each of the upper chambers, the partition wall between the intermediate and upper cham-

bers having openings adjacent the vertical partition of the uppermost chambers, said vertical partition having a transverse opening to provide for a thorough circulation 5 of air through the intermediate chambers and the upper chambers and a warming oven at each side of the uppermost portion of the stove body and arranged adjacent the upper chambers.

10 In testimony that I claim the foregoing I have hereunto set my hand at Milwaukee, in the county of Milwaukee and State of Wisconsin.

SIGMOND G. WEILER.
